UNITED STATES PATENT OFFICE.

EPHRAIM H. RODEN, OF CHICAGO, ILLINOIS.

MAILING DEVICE.

1,148,930.

Specification of Letters Patent.

Patented Aug. 3, 1915.

Application filed April 29, 1914. Serial No. 835,090.

To all whom it may concern:

Be it known that I, EPHRAIM H. RODEN, a citizen of the United States, residing at Chicago, in the county of Cook and State of Illinois, have invented certain new and useful Improvements in Mailing Devices, of which the following is a specification.

The invention relates to mailing devices or envelopes constructed in such a manner that may be used in connection with an opening device in the form of a stiff cardboard or other relatively stiff material in which, when the severing of the envelope is begun, a suitable cutting surface or surfaces on the opening device will complete the opening of the envelope to remove the contents thereof.

Other objects of the invention will appear from the following description, which is directed to the preferred embodiment of the invention, reference being had to the accompanying drawing forming a part of the specification.

In the said drawing,—Figure 1 is a view of the front side of an envelope, showing the manner in which a portion of the end to be opened is provided with cuts or slits in the nature of elongated perforations, by which the operator may remove a portion 25 of the envelope surrounded by the said slots or perforations by a pull on the same with his hand, and without the use of any instrument; Fig. 2 is a view similar to Fig. 1, showing the envelope in the act of being opened, almost the entire end being severed from the body of the envelope; Figs. 3 and 4 illustrate modified forms of the invention, the departure from the form of construction of Figs. 1 and 2 being merely in the manner of perforating the portion of the envelope which is detachable in the opening operation.

In the form of the invention shown in Figs. 1 and 2, the body of the envelope is designated by the reference character 10, while an opening device of relatively stiff cardboard is indicated by the reference character 11, Fig. 2. This member 11 is preferably of a stiff cardboard, of a size of the 45 interior of the envelope, except that at one end adjacent the end of the envelope desired to be opened the rectangular corners are cut on angular lines, as indicated at 11^a, Fig.

2. The envelope adjacent one end is provided with a portion 10^a that is semi-circular in form, being bounded by a plurality of

parallel perforations extending through both walls of the envelope and arranged in the manner of the perforations indicated by the reference character 10^b, Fig. 1. The perforations 10^b, when arranged in the semi-circular arrangement and spaced apart as shown in Fig. 1, will, when a pull is made upon the portion 10^a by grasping the same between the thumb and finger or fingers of the operator's hand, fracture or tear upon the lines of fracture as indicated by the drawing, Fig. 2. When the part 10^a fractures and separates from the body of the envelope, the insert or opening device 11 may then be pulled outwardly and the angular edges 11^a will sever or fracture the end of the envelope beyond the opening made by the separation of the part 10^a from the body of the envelope, after which the contents of the envelope may be removed, if the same have not been removed by the pulling out of the cutting insert 11. Although the preferred construction is that shown in Figs. 1 and 2, it is found that the part 10^a, which is to be separated from the body of the envelope by a pull, may be perforated in the manner shown, for example, in Figs. 3 and 4, and fair results secured, although for most conditions the manner of perforation shown in Figs. 1 and 2 is to be preferred. In Fig. 3, the envelope is indicated by the reference character 13, and the perforations are shown at 13^b, the removable portion being indicated at 13^a. In Fig. 4, the envelope 20 40 50 60 70 80 90 100 110 120 130 140 150 160 170 180 190 200 210 220 230 240 250 260 270 280 290 300 310 320 330 340 350 360 370 380 390 400 410 420 430 440 450 460 470 480 of the envelop and extending through the front and back thereof, and an insert in and substantially fitting the envelop and having one edge shorter than and engaging the inner side of the part of said edge of the envelop in the detachable portion, there being an edge on the insert at each end of said first mentioned edge thereof disposed at an angle to the latter and providing 10 means for severing the remainder of said

edge of the envelop after the detachable portion is removed.

In testimony whereof I have signed my name to this specification, in the presence of two subscribing witnesses, on this 25th 15 day of April, A. D. 1914.

EPHRAIM H. RODEN.

Witnesses:

A. L. SPRINKLE,
ALLENA OFFUTT.
